UNITED STATES PATENT OFFICE.

CHARLES HENRY SCANLAN, OF SAN FRANCISCO, CALIFORNIA.

DESIGN FOR A BADGE.

SPECIFICATION forming part of Design No. 15,118, dated July 1, 1884

Application filed October 19, 1883. Term of patent 31 years.

To all whom it may concern:

Be it known that I, CHARLES HENRY SCANLAN, a citizen of the United States, residing in the city and county of San Francisco, State of California, have invented and produced a new and original Design for a Badge, of which the following is a specification, reference being had to the accompanying drawing, forming part thereof.

- 10 My design relates to a badge in the form of a shield having the emblems shown in the eagle, harp, shamrock, and the sunburst. The sunburst is shown upon the uninscribed tomb, with the phenix rising from the same, and 15 above the phenix as a central figure is the representation of another bust, while above the head of the same, in the very center of the shield which forms the background of the

whole, are placed the clasped hands. Between the busts, upon the right and left side of the shield above the harp and beneath the eagle, surmounting the whole, is space for an inscription. The border is composed of shamrock wreathed up the sides from beneath the tomb, as shown. These emblems may be slightly 25 varied as to their arrangement, but the same general grouping of the design is to be maintained.

What I claim is—

The design for a badge, consisting of the 30 shield having the ornamentation shown and described.

CHARLES HENRY SCANLAN.

Witnesses:

JOHN H. REDSTONE,
L. E. REDSTONE.
